UNITED STATES PATENT OFFICE.

PAUL A. BANCEL, OF NUTLEY, NEW JERSEY, ASSIGNOR TO INGERSOLL-RAND COMPANY, OF JERSEY CITY, NEW JERSEY, A CORPORATION OF NEW JERSEY.

TWIN MULTIJET CONDENSER.

Application filed March 8, 1923. Serial No. 623,598.

To all whom it may concern:

Be it known that I, PAUL A. BANCEL, a citizen of the United States, and a resident of Nutley, county of Essex, and State of New Jersey, have invented a certain Twin Multijet Condenser, of which the following is a specification, accompanied by drawings. This invention relates to twin low level multi-jet condensers, but more particularly to balancing means connected between the twin condenser bodies.

By connecting a balancing pipe between the ejectors one condenser can be started in operation while the other condenser is running and the vacuum breaker on the condenser which is starting will be prevented from blowing, because the surplus water is drawn out of the throat of the condenser which is running and ejected to atmosphere. By drawing some of the water out through the balancing pipe from the condenser which is started, that condenser may continue to receive water, as the valve on the supply for that condenser is opened and in this way sufficient velocity is built up to cause the condenser to operate in the normal way.

The advantages of my balancing pipe construction, in addition to those stated, reside in the fact that one condenser can be readily and conveniently shut down when not required, as for instance in cold weather when only one condenser is necessary to hold the same vacuum with cold water; and since all light loads can be carried on one condenser, and when the peak load comes, the other condenser can be thrown into operation; the complete outfit is more flexible, because there is in effect two complete units having two supply pumps, and if one unit breaks down or goes out of service for any reason, operation can still be carried on with the other unit; and as a further advantage the balancing pipe itself affords a means for draining one condenser for starting operation.

The invention is illustrated in the accompanying drawing, which is a longitudinal sectional elevation of a twin low level multi-jet condenser, partly in diagrammatic form, without such details as are not necessary to the understanding of the invention.

Referring to the drawings, the twin condenser comprises the substantially circular up-right condenser bodies, A and B, having the usual diffusers or ejectors C and D, and

tail pieces E and F, which tail pieces are 55 submerged below the water level G in the sump or tank H having the wier J and outlet K. The tail pieces as shown are provided with the counter-weighted flap valves L and O and as shown, the valve L is open 60 since the condenser A is in full operation and the valve O is closed since the condenser B is starting to operate.

In the present instance, a common unitary connecting steam and water inlet head P extends over both the condenser bodies A and B, as shown in my co-pending application, Serial No. 623,599 filed March 8, 1923, and this head is provided with the openings in its lower end adapted to be fitted to the condenser bodies respectively. The upper opening of the common head is adapted to be fitted to a casing Q which may be the casing of a turbine or other prime mover from which the steam is supplied to the condenser. The connecting head P connects the twin condenser bodies to each other and also connects them with the turbine casing.

The head P is provided with the water inlets R and S for the condensers A and B respectively and in accordance with my construction each inlet is assumed to be supplied with water from a separate supply pump (not shown). The water passes to the nozzle plates T and U having the nozzles V and W forming multi-jets directed towards the throats X and Y of the condenser bodies A and B respectively. Each condenser body is also preferably provided with combining tubes formed with the operating guide vanes Z between which the steam passes to the jets. The condenser bodies A and B may each be provided with vacuum breakers, one vacuum breaker α being shown on the body B of any suitable or standard construction.

The balancing pipe b is shown connecting one condenser body with the other and a valve c is preferably provided in the pipe b. This balancing pipe b preferably connects the throat of one condenser body with the throat of the other above the diffusers C and D, and in the drawing, water is shown as being drawn off from the throat of the condenser B to the throat of the condenser A and thence ejected to atmosphere.

In the operation of the apparatus, let it be assumed that the condenser B is under

vacuum, but no load. In such case, the condenser B may be started and the vacuum breaker α will be prevented from operating or blowing because the surplus water from the condenser B is drawn off over to the throat of the condenser A. The condenser B can thus keep receiving water and sufficient velocity will be built up to cause the ejector of the condenser B to operate in the 10 normal way.

I claim:

1. A twin low level multi-jet condenser, comprising a pair of up-right condenser casings having diffusers, and tail pieces provided with valves, said tail pieces being adapted to be submerged, nozzles within the condenser casings for producing water jets, a balancing pipe connecting one casing with the other at points above the diffusers, and a 15 20 valve in said balancing pipe whereby one

condenser may be started while the other is under vacuum and load.

2. A twin low level multi-jet condenser, comprising a tank, a pair of up-right condenser casings, each having an outlet or throat at its lower portion, diffusers connected to said throats, tail pieces for said diffusers provided with valves and adapted to be submerged, nozzles within the condenser casings for producing water jets, a 25 30 balancing piping connecting the throat of one condenser casing with the throat of the other condenser casing at points above the diffusers, and a valve in said balancing pipe whereby one condenser may be started while the other is under vacuum and load.

In testimony whereof I have signed this specification.

PAUL A. BANCEL.
